UNITED STATES PATENT OFFICE.

JOHN RICHARDS, OF SAN FRANCISCO, CALIFORNIA.

HYDRAULIC RAM.

SPECIFICATION forming part of Letters Patent No. 357,413, dated February 8, 1887.

Application filed July 14, 1886. Serial No. 207,906. (No model.)

To all whom it may concern:

Be it known that I, JOHN RICHARDS, a citizen of the United States, residing at San Francisco, in the county of San Francisco and State 5 of California, have invented certain new and useful Improvements in Hydraulic Rams; and I do declare the following to be a full, clear, and exact description of the invention, such as will enable others skilled in the art to which it applies 10 to make and use the same, reference being had to the accompanying drawing, and to the letters and figures of reference marked thereon, which forms a part of this specification.

This invention relates to hydraulic rams for 15 raising water; and it consists in the construction, arrangement, and combination of parts, substantially as will be hereinafter described and claimed.

The annexed drawing represents a view in 20 elevation of my improved hydraulic ram, the valve-chamber being shown in section to expose the compound valve within.

A represents the main body of the ram, into 25 which the water enters through the pipe G. This body branches into two divisions, B and C, one of which, as C, leads to the valve-chamber D, and the other, as B, to the air-vessel E and the discharge F. The arrows upon the drawing indicate the directions which the water takes in its several courses.

The escape-valve, located in the chamber D, 30 is compound, consisting of the two parts H and I, which close the two outlets J and K in said chamber. The closure takes place when the valve-stem L is raised.

The respective areas of the two parts H and I of the compound valve are preferably of different sizes, the top one, H, being the larger. This difference of area is so measured and 40 regulated as nearly as possible that the weight of the valves and their attachments may be supported under the static pressure of the water. As this pressure, however, varies with the head of water employed to operate the 45 ram, it becomes necessary to use supplemental means to open or close the valve, which means consist, preferably, of a chamber or box, P, secured to the valve-stem L, and a balance-weight, Q, carried by a lever, R, fulcrumed 50 upon a support, and whose inner end engages the valve-stem. The chamber P is adapted to receive weights when the pressure of water is

greater than the weight of the valves alone can overcome, and by the addition of these weights a proper balance is attained and the 55 valves descend and open, and the balance-weight Q assists the valves to close when the head of water is not enough to cause such action by reason of the difference of area between the valves H and I. The weight Q is adjustable along the lever R, according to the amount of leverage that is necessary to overcome the water-pressure. It will be understood, however, that these devices just described are not essential to the successful operation of the ram 60 when the water-pressure and the difference between the areas of the valves is enough to sustain, or nearly sustain, the weight of the valves and their attachments. In this way a hydraulic ram may, after it has been constructed and 65 tested, be adapted to various heads of water.

In operating the ram, when the water is at rest the valve-stem L sinks under the action of gravity, thus allowing the water to escape at J and K, as indicated by the arrows. When the current increases in speed and force, the 70 escaping water at J impinges against a curved shield, O, located above said opening J, and formed integrally with the weight-receiving chamber P, above described, and by means of 75 said shield the course of the current is reversed and a reaction ensues. The valves and the stem L are thus caused to rise and arrest the flow, not suddenly and violently, as when the action of the water on the valve H is the 80 sole power for effectuating this result, but with a gentle force, owing to the difference in area between valves H and I, the final closing pressure being proportioned to this difference in area and not to the whole area of escape, as is 85 common in machines of this kind. As we have already seen, if the head or static pressure of the water is too much to allow the valve to sink and open weights are added to the chamber P, and if the static pressure is not 90 enough to sustain the valves and their attachments the balance-weight Q is used. When the valves H and I are closed, the course of the water in that direction is arrested, and it will therefore pursue an upward course into the 100 pipe B, being driven by its own impetus upward through the valve S into the chamber T and air-vessel E, whence it escapes through a discharge-pipe, inserted at F in the usual man-

ner. When the flow ceases, the valve-stem L sinks again, and the operation is repeated at regular intervals of time.

Having thus described my invention, what I claim as new, and desire to secure by Letters Patent, is—

1. The combination, with the escape-valve of a hydraulic ram, of a deflecting-shield, and a chamber for receiving weights formed integral with said shield and secured together therewith to the valve-stem, substantially as described.

2. The combination, with a double-seated valve, of a deflecting-shield secured to the valve-stem, a chamber for receiving weights

also secured to said stem, and a fulcrumed arm carrying a weight and engaging said stem, substantially as and for the purposes described.

3. The combination of the escape chamber having upper and lower openings, the double-seated valve within said chamber, the weight-holder secured to the stem of said valve, and the weighted lever, all arranged to operate as described.

In testimony whereof I affix my signature in presence of two witnesses.

JOHN RICHARDS.
